UNITED STATES PATENT OFFICE.

WILLIAM BOTT, OF COLUMBUS, OHIO.

DESIGN FOR A GAME-BOARD.

SPECIFICATION forming part of Design No. 30,467, dated April 4, 1899.

Application filed February 11, 1899. Serial No. 705,346. Term of patent 7 years.

To all whom it may concern:

Be it known that I, WILLIAM BOTT, a citizen of the United States, residing at Columbus, in the county of Franklin and State of Ohio, 5 have invented and produced a new and original Design for a Game-Board, of which the following is a specification, reference being had to the accompanying drawings, forming part thereof, and in which like characters refer 10 to correspondingly-formed parts.

My invention relates to a design for a game-board, and is fully illustrated in the accompanying drawings, in which—

Figure 1 is a top plan view of a game-board 15 embodying my invention. Fig. 2 is a central vertical sectional elevation thereof on line X X of Fig. 1, and Fig. 3 is a similar view thereof on line Y Y of Fig. 1.

In said drawings, 10 represents the game-board, provided on its opposite long edges with vertical straight walls 11 and 12 and on its opposite short edges, respectively, with a semi-circular vertical wall 13 and a substantially straight wall 14, connecting said walls 11 and 20 12. Adjacent said walls 11 and 12 and parallel therewith are vertical walls 17 and 18, extending from near the opposite ends of said wall 14 substantially to and at a slight distance from the points of beginning of said 25 wall 13, at which points said walls 17 and 18 terminate in points 19, as shown. Between

the walls 17 and 18 and 18 and 12 are respectively formed parallel grooves 20 and 21, substantially on a level with the board 10 and opening toward said curved wall 13, and in 35 the opposite ends of said grooves 20 and 21 are slots 22 and 23, respectively, passing through the board 10. At one end of said board 10 and adjacent to the wall 14 thereof is formed a rectangular slot 24, passing through 40 said board 10 and extending between the adjacent faces of said walls 17 and 18. At the ends of said slot 24 are rectangular slots 25 and 26 in the corners of said walls 14 and 11 and 12, said slots 25 and 26 extending from 45 the top and partially through said walls, as shown.

The essential feature of my design for a game-board consists of a game-board provided with grooves on opposite sides opening at one 50 end toward the curved end wall of said board and a slot passing through said game-board at its end opposite the curved end wall thereof.

What I claim is—

The design for a game-board, substantially 55 as shown and described.

In witness whereof I have hereunto set my hand this 6th day of February, 1899.

WILLIAM BOTT.
